United States Patent

Des. 239,263
Patented Mar. 23, 1976

239,263

COMBINED CLOCKFACE AND HANDS THEREFOR

Ke Won Lee, P.O. Box 2832,
Hialeah, Fla. 33012

Filed June 6, 1974, Ser. No. 476,922

Term of patent 14 years

Int. Cl. D10—01

U.S. Cl. D10—124

The figure is a plan view of a combined clockface and hands therefor, showing my new design which is of no appreciable thickness and the rear is plain and unornamented.

I claim:

The ornamental design for a combined clockface and hands therefor, as shown.
